UNITED STATES PATENT OFFICE.

ETHEL G. STAFFORD, OF SPRINGFIELD, ILLINOIS.

DENTAL FLOSS HOLDER.

Application filed September 19, 1927. Serial No. 220,339.

This invention relates to dental floss holders of that type wherein the floss from a bobbin or spool enclosed in a holder is to be tightly stretched for use in cleaning the teeth.

5 An object of the invention is that of providing for the bobbin or spool for the floss a cap frictionally held on the body of the device which when loosened for permitting the floss to be drawn from the bobbin will be held out of frictional engagement in a positive manner.

10 Still another object is to furnish a device of the character named with a member by which a used portion of the floss may be readily severed prior to presenting a new and unused portion for use.

15 Other advantages will appear in the following specification aided by the accompanying drawing wherein:

Figure 1 is a side elevation of a dental floss holder according to my invention.

20 Figure 2 is a longitudinal section of the same.

Figure 3 is a transverse section of a bobbin or spool and a shaft for controlling it.

25 Figure 4 is a transverse section of a body portion of the holder much enlarged.

Figure 5 is a side elevation of part of a tubular handle also much enlarged.

30 Figure 6 is an enlarged longitudinal section of parts of the device shown in Figure 2.

Figure 7 is an enlarged side elevation of a bobbin or spool and a shaft for its control.

35 Figure 8 shows in perspective a novel form of tip for an arm upon which to secure the end of the floss.

Figure 9 is a sectional elevation of the same, and

40 Figure 10 is a plan of a part of a handle portion showing a floss severing member attached thereto.

The holder includes a body portion 1 having integral laterally extending spaced arms 2 and 3 across which the floss denoted at 4 is drawn, a tubular handle portion 5, and a cap 6, all of which are well known except as to the details to appear herein.

45 The body portion 1 has an extended hollow portion 7 and in the wall of said body in the bottom of the bore of said portion 7 is a socket 8 forming a bearing for one end of a shaft 9 to be described in detail presently.

50 The arm 3 is provided with a slit 3' as in common practice. Also, the arm 2 is provided with a slit 2' in line with the slit 3'. Further, the arm 2 also has a groove 2² encircling it with which the said slit 2' communicates.

The said portion 7 receives into it one end of the said tubular handle 5, the latter being provided with a slot 10 opening through that end, and, in addition, there is a slot 11, or it 60 may be a groove, in said end of the handle which has an angular position extending from the extremity to a point inward from such extremity and may be likened to part of a thread, i. e., disposed in a spiral. Extending from the inner wall of the hollow extension 7 is a projection or nib 12 adapted to engage in the slot 11. That is to say, the handle when entered into the extension is so directed that the nib is made to enter the slot and by 65 turning said handle that member is drawn into the body 1 in the same manner as a bolt is drawn into a nut. The relation of the nib 12 and slot 11 are such, with respect to the slot 10, that upon the handle reaching its limit 70 of rotary movement the said slot 10 lies in line with the arms 2, 3 as may be understood from Figure 2.

The shaft 9 already referred to besides seating in the socket 8 extends through the cap 6, 80 being secured in any suitable manner therein, as by threads 13, for example, Figure 6. Said handle at the end having the cap is given a long taper, as 14, in the figure last named, and the cap has a tapered bore 15 to correspond 85 with and fit the same, the end of the handle being closed with the shaft extending through the same and free to shift therethrough, and said shaft may have a pin 16 in it to limit the shifting movement although other methods 90 may be used for thus limiting that movement.

A spring 15' is interposed between the cap and handle, Figure 5, whose purpose will appear.

95 A bobbin or spool denoted at 17 is slidable along the shaft 9 but the latter is flattened as at 18, Figures 3 and 6, and the tubular portion of the bobbin is flattened at 19 to engage the flat surface preventing the two turning relatively.

100 Secured on the handle 5 near the body 1 is a floss severing member 20 which may be riveted in place, and, as shown in Figure 10, a portion thereof is spaced from said handle to permit the floss to be carried in behind it 105 upon a sharpened portion thereof, 21, within a notch 22 for example.

110 Also secured on the handle is a clip 23 by which the device may be securely attached to the clothing of the user. If it is desired to suspend the device from a chain or cord, the cap 6 may have secured thereto in any good

manner a ring 24 for attachment thereto of said chain or cord, not shown.

When the parts of the device are assembled the closed terminal of the slot 10 of the handle 5 lies just outside the extension 7 of the body 1 leaving an opening through which the floss may be drawn from the bobbin 17, and since the latter may freely shift lengthwise of shaft 9 the floss will be drawn therefrom without effort lengthwise of the shaft when that member is released by disengaging the cap 6 from the handle, said bobbin following along the shaft with any given convolution of the floss always opposite the said opening.

Since the cap 6 may be loosened from the handle, and since, also, the shaft 9 is fixed in said cap, such loosening of the latter will permit it, the bobbin and the cap to rotate when the floss is drawn from said bobbin. The end of the floss is drawn through the slits 3' and 2', thence being wound once or twice within the groove 2² and thence again back through the slit 2' if desired. Due to winding the floss in the slit and groove it is clear that it will be very positively held so that no amount of strain or pull will withdraw the floss from the arm 2.

Having thus secured the floss the cap 6 is now turned to tighten the floss across the arms 2 and 3 by rotating the bobbin, said cap at the same time being carried into snug frictional engagement with the handle compressing the interposed spring 15', the device now being ready for use. The said spring 15' is provided in order that upon loosening the cap that member will be carried clear of any frictional engagement insuring that the bobbin will be entirely free to rotate and that there will be no friction between the cap and handle. However, such spring has not sufficient tension to separate the cap from the handle when these parts are carried into engagement. The particular arrangement of the frictional surfaces of the cap and handle may perhaps be departed from while permitting the desired action and the advantages to be derived therefrom.

While I have shown the slit 2' in the end of the arm 2 as severing said arm down to the groove 2² as in Figure 9, said slit may be otherwise produced so long as the required result of positively holding the floss is produced.

55 I claim:

1. In a dental floss holder, the combination of a body portion, a tubular handle extending therefrom, a cap to engage the outer end of the handle, one of the last named mem-

bers being tapered and the other having a 60 tapered bore complementary thereto, the two members adapted to be fixed relatively in a desired adjustment through frictional engagement by endwise pressure of one on the other, and a bobbin in said handle operatively 65 engaging the cap and turned thereby.

2. In a dental floss holder, the combination of a body portion, a tubular handle extending therefrom, a cap to engage the outer end of the handle, one of the last named members being tapered and the other having a tapered bore complementary thereto, the two members adapted to be fixed relatively in a desired adjustment through frictional engagement by 70 endwise pressure of one on the other, a bobbin in said handle operatively engaging the cap and turned thereby, and a compression 75 spring interposed between the handle and said cap.

3. In a dental floss holder, the combination of a body portion, a tubular handle extending therefrom, a cap to engage the outer end of the handle, one of the last named members being tapered and the other having a tapered bore complementary thereto, the two members adapted to be fixed relatively in a desired adjustment through frictional engagement by 80 endwise pressure of one on the other, a bobbin in said handle, a shaft affixed to the cap and operatively engaging the bobbin 85 whereby rotation of the said cap will rotate said bobbin, and a compression spring interposed between the cap and said handle.

4. The combination, in a dental floss holder including a hollow handle, a pair of spaced arms normally fixed at one end of the handle between which to stretch floss, the other end of the handle being tapered, a bobbin in said handle for carrying floss, a shaft on which the bobbin is slidably endwise but rotatably driven by said shaft, a cap having a tapered bore complementary to the tapered end of the handle and frictionally engaging the latter, said shaft being fixed to said cap, and a compression spring interposed between 100 the handle-end and the inner wall of said cap. 105

5. The combination with a dental floss holder including a hollow handle, a shaft in and extending longitudinally of the handle and having a flat surface extending therealong, and a bobbin including a sleeve portion upon which to wind floss, said sleeve portion having a part thereof depressed below the periphery thereof to form a flat surface within the bore of said sleeve to engage 110 upon the said flat surface of the shaft. 115

In testimony whereof I affix my signature.

ETHEL G. STAFFORD.
